UNITED STATES PATENT OFFICE.

JOHN B. INGRAM, OF LOS ANGELES, CALIFORNIA.

SWIMMER'S GLOVE.

Application filed April 23, 1921. Serial No. 464,012.

To all whom it may concern:

Be it known that I, JOHN B. INGRAM, a citizen of the United States, residing at Los Angeles, in the county of Los Angeles and 5 State of California, have invented new and useful Improvements in Swimmers' Gloves, of which the following is a specification.

It is the object of this invention to provide a glove for use by swimmers and having webs between the fingers of the glove. The improved glove is made of a suitable flexible material in order that the fingers may be readily moved relative to one another, the flexible webs between the fingers 15 folding or expanding as the fingers are thus moved.

The improved glove structure is, preferably, made with the palm of the glove cut away, and the said glove is preferably 20 adapted to be buttoned on the hand, the glove being cut away at the base of the palm or just below the fingers.

In practice, the back of the glove is preferably provided with openings, in order 25 that a free outlet is provided for any water collecting within the glove.

The invention will be readily understood from the following description of the accompanying drawings, in which—

30 Figures 1 and 2 are a back view and a palm view showing a form of the invention.

The glove shown in the form of the invention illustrated includes, fingers 1, thumb 2, the palm portion 3 and the back 4 provided with a button connection 6 for fastening the glove upon the hand. The glove may be made of suitable flexible material such as canvas or rubber, and webs 7 are provided between the fingers and between

40 the latter and the thumb 2. These webs are also of flexible material and may be made of a material which is elastic as well as flexible, in order to readily expand and con-

tract as the fingers are moved toward and away from one another.

45 The back of the glove is preferably provided with slots 9 in order to permit of the ready outlet from the glove of any water which may collect therein.

In order to permit free movement of the 50 hand, the palm of the glove is cut away above the wrist portion of ordinary gloves, as shown at 10, and the remaining portion is preferably cut away as at 8.

The device as just described provides a 55 glove adapted to assist a swimmer by providing webs between the fingers of the glove, and the glove at the same time, will not hinder the free movement of the hand due to the cut away portions of the glove. The 60 provision of slots in the back of the glove will also prevent the accumulation of water therein.

Various changes may be made without departing from the spirit of the invention as 65 claimed.

What is claimed is:

A swimming glove having finger and thumb receiving portions, webs between said finger and thumb receiving portions, there 70 being an opening formed in the palm portion of the body of the glove, there being a plurality of longitudinally disposed slots formed in the back portion of the body of the glove, the palm and back section of the 75 glove terminating immediately to the rear of the thumb portion of the glove so as to leave the rear portion of the palm of the wearer exposed, and fastening means for securing the rear portion of the glove around 80 the palm and back portion of the wearer's hand.

In testimony whereof I have signed my name to this specification.

JOHN B. INGRAM.
